UNITED STATES PATENT OFFICE.

GEORGE HARRIOTT, OF TOLEDO, OHIO, ASSIGNOR TO THE GENDRON IRON WHEEL COMPANY, OF SAME PLACE.

BICYCLE.

SPECIFICATION forming part of Letters Patent No. 439,400, dated October 28, 1890.

Application filed May 10, 1890. Serial No. 351,352. (No model.)

To all whom it may concern:

Be it known that I, GEORGE HARRIOTT, a subject of the Queen of Great Britain, residing at Toledo, in the county of Lucas and State of Ohio, have invented certain new and useful Improvements in Bicycles, of which the following is a specification, reference being had therein to the accompanying drawings.

10 This invention relates to new and useful improvements in bicycles of that kind known as "Safety;" and the invention consists in the improved construction and arrangement of the seat and seat-supports, all as more fully 15 hereinafter described, and shown in the accompanying drawings, in which—

Figure 1 is a side elevation of a bicycle embodying my improvements. Fig. 2 is an enlarged elevation of the seat, partly in section. 20 Fig. 3 is a plan of Fig. 2, with some of the parts shown in dotted lines only. Fig. 4 is a cross-section through the tension device on line *v v* of Fig. 2. Fig. 5 is an end elevation of the tension device. Figs. 6 and 7 are detached perspective views of the plates forming the seat-frame.

A is a steering-wheel, and A' the driving-wheel, both substantially of the same diameter.

30 B and B' are the front and rear forks, between the arms of which said wheels are mounted, respectively.

C is the front upright, preferably formed of steel tubing.

35 C² is a steering-lever secured to a spindle C', which engages into the front fork-upright and is adjustably secured therein by means of a clamping-collar C³, which engages upon a reduced and slotted portion C⁴, formed on the upper end of the upright, and is provided with a clamping-screw C⁵, whereby the tightening of said screw clamps the parts together.

40 D D' are two collars secured upon the front upright and provided with rearwardly-extending lugs D² D³, which form the steering-head, to which the front end of the spine is pivotally connected.

The arm F' is formed in one piece with the brake-shoe F. It is pivotally secured to the

knuckle D⁴, and extends forwardly on top of 50 the wheel, and is guided between the upper ends of the arms of the front fork.

The brake-rod F² is pivotally connected at its lower end to the brake-shoe and its upper end to the brake-lever F³, which latter is pivotally secured to the steering-lever. The coupling or turn-buckle F⁴ in the brake-rod permits of its being lengthened or shortened.

The spine H is hollow and preferably made of steel tubing curved at its forward end over 60 the front wheel, extending horizontally to the rear and joined to the rear fork to form a rigid frame. Upon this frame is mounted in suitable bearings the crank and sprocket-shaft I of the driving-gear, which consists of 65 the usual cranks, sprocket-wheels, and chain.

J is the rear upright secured at its lower end to the frame, curved at its lower portion over the front part of the rear wheel, and then extending vertically upward. It is prefer- 70 ably formed of steel tubing and provided at its upper end with the clamping-collar K, by means of which the seat-supporting post L is vertically adjustably secured in the upper end of the upright. This post has a 75

grooved arm L' at its upper end at right angles and carries the seat. This seat consists of the usual leather saddle M, secured at its front and rear end, respectively, to the metal frame-plates N and O, and which are supported upon front and rear springs P and Q. 80 Each of these springs is formed of one piece of suitable spring-wire, with a pair of coils a connected on top by a rectangularly-bent portion b and with the projecting ends c. These 85 springs are engaged with the portions b into suitable seats d d', formed on the plates N and O, respectively, and with the straight end portions c into sockets formed in the sliding plates R, which form part of the seat-block. This consists of the bed-plate S, pro- 90

vided with a sleeve T on the under side for adjustably securing it with a set-screw T' upon the grooved arm of the seat-supporting post L. On top of the bed-plate is sup- 95

ported in bearings U the right and lefthanded spreader-screw V', engaged, respectively, into screw-threaded sockets of the sliding

plates R. Between the bearings the screw is provided with a head W for turning it by means of a wrench, all so arranged that by turning the screw in the proper direction the two sliding plates R R, which have a tenon-and-mortise engagement with the bed-plate S, are spread apart, and thereby bring the springs P and Q under any desired tension required to keep the saddle M taut. This construction is obviously simple and permits the stretching of the saddle without displacing it from its adjusted position. At the same time it is readily mounted and dismounted, and affords easy riding, a suitable inclination being given to the saddle by making the coils of the rear spring of larger diameter than the coils of the front spring.

By providing the arm L' of the seat-supporting post with the longitudinal groove and engaging the said screw T' into this groove the seat maintains its proper position when the seat-block is adjusted. The coils a of the springs are on both sides of the connection with the saddle, and the rectangular bends b are seated in the frame-plates and hold the saddle against any displacement and bring the tension of the springs to stretch the saddle longitudinally. The improvement in the front upright and the parts connected therewith I have made the subject of a separate application for Letters Patent, filed May 13, 1890, Serial No. 351,700.

What I claim as my invention is—

1. In a bicycle, the combination, with a seat-supporting post L, of the bed-plate S, adjustably secured thereto, the sliding plate R on the bed-plate, the spreader-screw V', adjustably connecting the sliding plates by right and left hand threads, respectively, and secured in bearings upon the bed-plates S, the front and rear springs P and Q, having arms c, secured in sockets in the sliding plates R, and the saddle M, secured to the springs P and Q, respectively, substantially as described.
2. In a bicycle, the combination, with the seat-supporting post L, of the bed-plate S, adjustably secured to said post, the plates R, slidingly engaging with the bed-plate S, the

spreader-screw V', provided with right and left hand screw-threads at opposite ends and 50 engaging with the plates R, the bearings U, in which the spreader-screw is supported upon the bed-plate, the head W of the spreader-screw arranged between said bearings, the front and rear springs P and Q, provided with 55 arms c, engaged to the sliding plates R, respectively, and with the straight portion b, the saddle M, provided with the frame-plates N and O, secured to the opposite ends of the saddle and provided with the seats d, into 60 which the springs are engaged, substantially as described.

3. In a bicycle, the combination of the seat-block provided with the longitudinally-adjustable plates R, of the saddle M, provided 65 with frame-plates O and N, secured to opposite ends thereof, the springs P Q, each formed with two coils at both sides of its connection with the saddle, and with the coils of the rear spring larger than the coils of the front spring, 70 the angularly-bent portions b of these springs engaged in sockets d d' of the frame-plates, and the straight ends c of these springs engaged into sockets of the sliding plates R, respectively, substantially as described. 75

4. In a bicycle, the combination of the vertically-adjustable seat-supporting post L, having the longitudinally-grooved arm L', and provided with a set-screw engaging into the groove of the arm L', the plates R, having a 80 sliding dovetail mortise-and-tenon engagement upon the opposite ends of the bed-plate, the screw V', journaled in bearings U upon the bed-plate and provided with the head W, and right and left handed screw-threads upon 85 its opposite ends, engaging with the plates R, respectively, and a saddle having its front and rear ends independently supported by the plates R R, substantially as described.

In testimony whereof I affix my signature, in 90 presence of two witnesses, this 19th day of February, 1890.

GEORGE HARRIOTT.
